(57) CLAIM

The ornamental design for a combination pen, stylus and light, as described and shown.

DESCRIPTION

FIG. 1 is a perspective view of the combination pen, stylus and light, with the cap in the closed position, showing my new design.

FIG. 2 is a left side elevation view thereof, the right side view being a mirror image of the left side view.

FIG. 3 is a bottom plan view thereof.

FIG. 4 is a top plan view thereof.

FIG. 5 is a front elevation view thereof.

FIG. 6 is a rear elevation view thereof.

FIG. 7 is a perspective view thereof, with the cap posted on the rear, exposing the pen tip.

FIG. 8 is a left side elevation view thereof, the right side view being a mirror image of the left side view.

FIG. 9 is a bottom plan view thereof.

FIG. 10 is a top plan view thereof.

FIG. 11 is a front elevation view thereof; and,

FIG. 12 is a rear elevation view thereof.
